E. C. PLOENSE

THREAD CLEAVER

Filed Dec. 18, 1923

Fig. 2.

Emil C. Ploense,
Inventor

By *Clarus Attornies*
Attorneys

UNITED STATES PATENT OFFICE.

EMIL C. PLOENSE, OF BLOOMINGTON, ILLINOIS.

THREAD CLEARER.

Application filed December 18, 1923. Serial No. 681,374.

To all whom it may concern:

Be it known that I, EMIL C. PLOENSE, citizen of the United States, residing at Bloomington, in the county of McLean and 5 State of Illinois, have invented certain new and useful Improvements in Thread Clearers, of which the following is a specification.

This invention relates to certain new and 10 useful improvements in thread clearing implements and has particular reference to a device adapted for use in removing cuttings from threads of the threaded wall of an opening which has been duly tapped.

15 The primary object of the invention is to provide a thread clearing implement of the above kind which embraces the desired qualities of simplicity and durability of construction, as well as efficiency in operation.

20 Another object of the invention is to provide a thread clearer which may be cheaply and easily manufactured and placed into use, and wherein the structure is such that the device may not readily become damaged 25 or broken.

A further object of the invention is to provide a thread clearer of the above kind which may be readily adjusted to engage the threads in the walls of different sized openings.

30 Other objects will appear as the nature of the invention is better understood, and the same consists in the novel form, combination, and arrangement of parts herein- 35 after more fully described, shown in the accompanying drawing and claimed.

In the drawing, wherein a preferred embodiment of the invention is shown, and wherein like reference characters designate 40 corresponding parts throughout the several views:

Figure 1 is a view partly in plan and partly in longitudinal section of a thread clearer constructed in accordance with the 45 present invention.

Figure 2 is a transverse sectional view, taken substantially upon the line 2—2 of Figure 1, and

50 Figure 3 is a view similar to Figure 2 drawn on a larger scale and illustrating a modified form of the invention.

Referring more in detail to the drawing, the invention comprises a metallic body 5, from one end of which projects a plurality 55 of legs 6 that are preferably disposed in

outwardly diverging relation as shown and have laterally directed free end portions 7, the extreme ends of which are formed or pointed, as at 8, to fit in or engage the walls of the thread to be cleared. The form of 60 implement shown is adapted for clearing internal threads, and the end portions 7 of the legs 6 are therefore outturned as clearly illustrated in Figure 1. The body 5 is provided with any suitable means for facilitating turning or rotation thereof, and this means is shown as comprising a pair of lateral oppositely positioned handles or hand grips 9 rigid with the body 5, and extending 65 from the sides thereof.

70 Means is provided for expanding the legs 6 or permitting contraction thereof so that the device may be accommodated to threads of different sized openings or the like. In the form of the invention shown, this means 75 comprises cam lugs 10 provided on the adjacent sides of the legs 6 at the inner ends of the latter, and an adjusting screw 11 that is threaded through the body 5 axially 80 of the latter and that is provided with a tapered inner end as at 12 engaging the outwardly converging edges of the cam lugs 10. It will be seen that when the set screw 11 is threaded inwardly, the inner end thereof 85 will engage the cams 10, so as to expand the legs 6 which are preferably normally contracted.

90 The body 5 is shown herein as an integral member having the legs 6 integral therewith, and in order to permit the ready expansion or separation of the legs 6, the outer end portion of the body 5 is provided with longitudinal slots 13 corresponding in number to the number of legs 6 employed and positioned in planes substantially midway between the planes of said legs 6. The inner end portion of the body 5 is unslotted, so as to provide for the connection of the leg carrying parts and permit their relative angular displacement during the expansion and contraction of the legs.

95 Also, the bore of the outer end portion of the body 5 is slightly larger than the diameter of the stem of the adjusting screw 11, so that the members 14 and 15 of said body that are formed by providing the slots 13 may have slight relative movement when the legs 6 are adjusted, the stem of the screw 11 having threaded engagement with the unslotted inner end portion of the body 5 as 100 105 110

clearly shown in Figure 1, at 16. The screw 11 may be provided with any means for facilitating its operation, such as a polygonal head 17 adapted for engagement by a wrench or the like.

In the form of the invention shown in Figures 1 and 2, the implement is disclosed as comprising a pair of the legs 6 disposed in opposed relation, but as shown in Figure 10 3, the number of legs may be increased. In the latter figure, the construction is exactly the same as that in Figures 1 and 2, except that three of the legs are provided as at 6' and three of the slots are provided as at 13' 15 in the body 5'. Otherwise, the construction in the form of the invention shown in Figure 3 will correspond to that shown in Figures 1 and 2.

In operation, the screw 11 is retracted, 20 so as to allow contraction of the legs 6, sufficiently to permit insertion of the latter within the threaded opening. The screw 11 is then adjusted inwardly to expand the legs 6 for engaging the pointed ends 8 thereof 25 in opposite portions of the thread to be cleared. The handles 9 are then grasped for imparting a rotary motion to the implement, and as the points of the legs 6 will follow the thread, cuttings will be effectively 30 cleared therefrom. To facilitate the re-

moval of the implement from the hole, it is simply necessary to thread the screw 11 outwardly for permitting contraction of the legs 6 and disengagement of the ends 8 thereof from the thread.

35

From the foregoing description, it is believed that the construction and operation as well as the advantages of the present invention will be readily understood and appreciated by those skilled in the art.

40

Minor changes may be made without departing from the spirit and scope of the invention as claimed.

What I claim as new is:

In a thread clearer of the character described, a body provided with a plurality of legs that project from one end thereof, said legs having laterally directed free ends formed to fit and engage within the threads to be cleared, means carried by said body for facilitating application of rotary motion thereto, an adjusting screw threaded axially through the body and having its inner end projecting between the inner ends of the legs, and cam lugs upon the adjacent sides 55 of the inner end portions of said legs engageable by the inner end of said adjusting screw for expanding the legs.

In testimony whereof I affix my signature.

EMIL C. PLOENSE.
